Primary Examiner — Ian Simmons*Assistant Examiner* — Dana L Meyrow(74) *Attorney, Agent, or Firm* — The Belles Group, P.C.(57) **CLAIM**

The ornamental design for a bottle, as shown and described.

DESCRIPTION

FIG. 1 is a perspective view of a bottle showing my new design;

FIG. 2 is a front elevation view thereof;

FIG. 3 is a side elevation view thereof;

FIG. 4 is a top plan view thereof, with the opposing side details seen through the transparent surface not being shown for ease of illustration; and,

FIG. 5 is a bottom plan view thereof, with the opposing side details seen through the transparent surface not being shown for ease of illustration.

The front and rear of the design are identical, as are both sides of the design. The broken lines in the drawings are included for purposes of illustration only and form no part of the claim.
